FABRIC OR THE LIKE

Simon Bochner, Yonkers, N. Y., assignor to Covington Fabrics Corporation, New York,
N. Y., a corporation of New York

Application September 6, 1951, Serial No. 16,544
Term of patent 3½ years

(Cl. D92—1)

To all whom it may concern:

Be it known that I, Simon Bochner, a citizen of the United States, residing at Yonkers, in the State of New York, have invented a new, original, and ornamental Design for a Fabric or the like, of which the following is a specification, reference being had to the accompanying drawing, forming part thereof.

In the drawing:

The figure is a plan view of a piece of a fabric or the like showing my new design. The design unit is outlined by dotted lines, which unit is repeated over the fabric as indicated by the extensions beyond the unit boundaries.

I claim:

The ornamental design for a fabric or the like, as shown and described.

SIMON BOCHNER.
